UNITED STATES PATENT OFFICE.

FRANZ ROBERT SCHUMACHER, OF CHICAGO, ILLINOIS.

TOBACCO-PIPE.

1,047,577.

Specification of Letters Patent. Patented Dec. 17, 1912.

Application filed January 27, 1912. Serial No. 673,732.

To all whom it may concern:

Be it known that I, FRANZ ROBERT SCHUMACHER, a citizen of the United States, residing at Chicago, in the county of Cook and State of Illinois, have invented certain new and useful Improvements in Tobacco-Pipes, of which the following is a specification.

My invention relates to improvements in tobacco pipes and more particularly to pipes wherein a removable cleaner tube is provided for the bore in the stem.

One of the objects of my invention is so to shape the parts that the tube may most effectively clean the pipe-stem and may itself be cleaned with minimum amount of trouble.

Another object of my invention is so to construct and arrange the parts that the cleaner tube has a smoke-cooling effect, acts effectively to connect the bit and stummel, and is readily detachable from both said parts.

Other objects will become apparent from the following description taken in conjunction with the accompanying drawing, wherein—

Figure 1 is a longitudinal central section of a straight-stem pipe to which my invention has been applied; Fig. 2 is a perspective view of the cleaner tube; Fig. 3 is an enlarged fragmentary view of the end thereof; Fig. 4 is a perspective view of a stummel-protecting sleeve; and Fig. 5 is a longitudinal central section of a "drop" pipe having a curved bit.

In the drawings, 5 indicates the bowl, 6 the stem, and 7 the mouthpiece or bit of a pipe, these parts being of any usual exterior construction. The stem 7 of the stummel is centrally bored, as at 8, the bore extending, preferably with uniform diameter, to a little beyond the perforation 8' communicating with the bowl. Such bore 8 may if desired have inserted therein a protecting lining or sleeve 9 provided near its end with an aperture 10 for register with the perforation 8'. The tube 9 is not necessary except where the material of which the stummel is formed requires greater protection than is afforded by the cleaner member to be described. For instance, meerschaum stummels may advantageously be lined, but

briar stummels serve well without the lining, as shown in Fig. 5.

The bit or mouthpiece 7 is formed to support the cleaner member which is to engage in the bore of the stem, and to this end I preferably make the bore of the bit tapered at its end, as at 11, for register with the bore of the stem, to effect frictional engagement between the bit and a correspondingly tapered portion of the cleaner member.

The cleaner member 12 is preferably formed of aluminum, or other material which will not affect the taste of the tobacco smoke, and may be economically constructed of sheet metal properly punched and then rolled to tubular form. At the bit end, the cleaner tube provides a tapered portion 13 which is adapted to engage frictionally in the tapered bore of the bit as above described. The cleaner tube 12 is thus carried by the bit. If necessary to reinforce the bit (as where the bit is of amber, say) a small bit-protecting tube 14 may be used to line the bore, and as shown in Fig. 2 such tube may be an integral extension of the cleaning member, as shown in Figs. 1 and 2. This extension may, however, be dispensed with, and in Fig. 5 I have shown the application of my invention without the tube and with a curved bit.

The portion of the cleaner member extending beyond the bit into the stem bore is shaped to constitute a lining tube for the bore of the stem and preferably extends clear to the end of the bore beyond the bowl-port 8', an aperture 15 being provided in the tube to register with said perforation 8' to bring the interior of the cleaner tube into communication with the bowl. Between the tapered zone 11 and the perforation 15, the tube has longitudinal strips cut away, as at 16, to leave a plurality of longitudinal, parallel, separated ribs 17, which may be bowed slightly outwardly to insure their spring-contact with the walls of the bore. To provide an end-cleaning blade, the end of the tube 12 is preferably partly closed as by turning down ears 18 from the cylindrical portion of the tube, the two ears jointly to form a blade, and the cylindrical portion of the tube, upon each side of the blade 18, is preferably cut away somewhat as at 19, to provide suitable end openings.

- In the use of a pipe provided with a cleaner as described, it will be observed that the cleaner tube may form the sole connection between the bit and stummel, making a wedge connection with the bit and slip connection with the stem. The passage of the smoke through the tube from the aperture 15 to the bit will have a cooling and drying tendency by reason of the size of the chamber and the provision of the spaces 16 in which the smoke may eddy and deposit its moisture. When the deposit incident to use of the pipe has become great enough to partly clog the spaces between ribs 17 and 10 the openings at the end of the tube 12, rotation of the bit and the cleaner tube carried thereby will cause the ribs 17 and blade 18 to scrape the exposed portions of the walls of the bore and gather up all of the semi-fluid deposit which may have adhered to them, so that when the cleaner is pulled out (by drawing back the bit) it carries all of the deposit with it, leaving the bore clear.

The deposit within the lining may now 25 easily be cleaned off as by washing under running water, the slits and end openings giving maximum access to the interior. Obviously, the cleaner may be detached from the bit simply by disengaging the coating 30 tapering surfaces 11-13, so that the tube may be cleaned apart from any of the larger parts of the pipe.

While I have herein described an embodiment of my invention, it will be apparent to 35 those skilled in the art that changes may be made therein without departing from the spirit of my invention and within the scope of the appended claims.

What I claim is:

- 40 1. In a tobacco pipe, the combination with a bowl, a stem and a bit, said stem and bit having registering bores, of a tubular member engaging in the bore of the stem and bit, and removable from the stem, said member 45 having in its sides longitudinally-extensive lateral openings and ribs laterally deflected to provide resilient surfaces in frictional engagement with the stem bore.
2. In a tobacco pipe, the combination with 50 a bowl, a stem having a bore communicating with the bowl, and a bit having a tapering bore registering with said bore of the stem, of a tubular member having a plurality of resilient longitudinally extensive ribs, at 55 one end frictionally engaging in said bore of the stem and having an opening for communication with the bowl and at its other end being tapered for frictional engagement in the tapering bore of the bit.
- 60 3. In a tobacco pipe, the combination with a bowl, a stem having a bore communicating with the bowl, and a bit having a registering bore, of a tubular member having a portion tapered and making wedge engagement 65 with the bit, and having another portion

providing a plurality of spring members making frictional engagement with the stem.

4. In a tobacco pipe, the combination with a bowl, a stem having a bore communicating with the bowl, and a bit having a tapering bore registering with the bore of the stem, of a tubular member, at one end engaging in said bore of the stem and having an opening for communication with the bowl, at its other end being tapered for frictional engagement in the tapering bore of the bit, and between its ends having laterally opening slits providing intervening ribs substantially as long as the bore of the stem. 70

5. In a tobacco pipe, the combination with a bowl, a stem having a bore communicating with the bowl, and a bit, of a cleaner member for said bore carried by the bit, said member being provided with longitudinally-extending laterally-bowed resilient ribs along 85 a portion of its length. 80

6. In a tobacco pipe, the combination with a bowl, a stem having a bore of substantially uniform diameter near its outer end, extending into communication with the bowl, 90 and a bit having a registering bore, of a tubular cleaner member constituting a smoke-cooling chamber, at one end engaging in the bore of the bit and at its other end engaging the stem to connect the two parts, 95 said member having an opening for communication with the bowl, and between its ends being cut away to form a plurality of slots and intermediate resilient ribs, said ribs engaging the interior of the stem and said member being rotatable in the bore of the stem and removable therefrom to gather up and remove the matter deposited in the eddy spaces within the member and between the ribs. 100

7. In a tobacco pipe having stem and bit members with registering bores, a cleaner member having suitable openings at its ends, said ends being formed for engagement in said registering bores in the stem and bit 110 members, and said cleaner member between said ends having a plurality of long ribs separated by eddy spaces. 105

8. In a tobacco pipe, the combination with a bowl, a stem having a bore communicating with the bowl, and a bit having a tapering bore, of a cleaner member having a ribbed portion for frictional engagement in the bore of the stem and a tapering portion for wedge engagement in the bore of the bit, 115 said tapering portion merging into said ribbed portion, whereby said cleaner member may be supported upon the bit by wedge engagement of its tapering portion in the tapered bore of the bit and the exposed 120 portion of said cleaner member inserted into the bore of the stem, the frictional engagement in said stem being less than the wedge engagement in the bit, for rotation of the cleaner in the stem by means of the bit. 125

9. A cleaner member for tobacco pipes comprising a tubular insert having an opening near one end for communication with the bowl of a pipe and a series of long eddy-space openings between said opening and the other end, the end of said member beyond said bowl opening having a blade partially closing said end.

In testimony whereof I hereunto set my hand in the presence of two witnesses.
